IMPROVEMENT IN STEAM-ENGINE CONDENSERS.

J. M. MILLER, OF NEW YORK, N. Y.

Letters Patent No. 60,222, dated December 4, 1866.

SPECIFICATION.

Be it known that I, JAMES M. MILLER, of the city, county, and State of New York, have invented certain new and useful Improvements in Steam Apparatus for transferring the waste heat from the exhaust of a steam engine back to the boiler; and I do hereby declare and ascertain my said invention as follows, referring to the accompanying drawings, in which—

Figure 1 is a vertical section through the apparatus.

Figure 2 is a vertical section on line *w w* of fig. 1.

Figure 3 is a side elevation of the apparatus.

Figure 4 is a horizontal section on the line *x x* of fig. 1.

Figure 5 is a horizontal section on the line *y y* of fig. 1.

Figure 6 is a horizontal section on the line *z z* of fig. 1.

Figure 7 shows the legs *d*, on casting *a*.

Figure 8 is an enlarged view of one of the tubes *b*.

The purpose of this invention is to more perfectly transfer the waste heat from the engine back to the steam boiler, with the least amount of power available, and to relieve the case containing the condensing and feed-water of pressure, by means of which I can make the tubes and other parts thin and at less cost than could otherwise be done, while I increase the efficiency of the apparatus, and produce a large economy of fuel.

The construction is as follows: *a a* represent oblong hollow castings, with parallel sides, the form of which is clearly seen in figs. 1, 2, and 4. The two broad sides of these castings are pierced with holes as indicated by the circles *b b*, fig. 2, and there are braces, *c c*, in the interior (see fig. 1) to stay the sides and prevent their collapsing. Two legs *d*, fig. 7, are cast on to the lower corners, on which the casting *a* stands. The holes above named in the casting *a*, are threaded to receive the ends of certain tubes *b b*, that are screwed into them; these tubes are of peculiar construction, as shown at fig. 8, in section, where it will be noticed the tube is made of very thin metal, with its closed end recurved inward, so as to form an annular chamber that communicates with the interior of the casting *a*, when the tube *b* is connected therewith. The end of the tube *b* that is screwed into the casting is made thick, the thickness projecting inward, so as to contract the opening into the chamber of the casting *a*. By this construction, a small quantity of condensed water is retained in the tube, which I deem advantageous. The proper number of tubes having been screwed into the casting or centre chamber *a*, perpendicular to its broad side, when the said casting stands erect in the inclosing case, they will be in a horizontal position, as clearly seen in fig. 1. Any desired number of such chambers are placed in an inclosing water-tight case *e*, the legs *d* being affixed to the base-plate *f* thereof. Two such chambers are shown in the drawing, and these chambers have no connection or communication with the said case *e*. The chambers *a* connect at the top with the exhaust-pipe, *g*, of the steam engine through which the exhaust steam passes into them. At the bottom of these chambers *a*, are openings that discharge the contents thereof into coils of pipe *h*. Located between the said chambers *a* and the bottom of the case, one or more coils are used for each section or chamber *a*, and they all terminate in a centre chamber *i*. From the under side of chamber *i*, below the base-plate *f*, there is a second series of coils of pipe, *k*, conveying the discharged and condensed steam to the vacuum pump *l*, which pumps it into the case *e*, that surrounds the tube chambers *a b*, and which is filled with pure hot water, which is thence caused to flow through the pipe *m* to the feed pump *n*, that forces it into the boiler. The coils of pipe *k* below the base-plate *f* are enclosed in a cold-water tank, which receives its supply of cold water from any convenient source. The case *e* should be supplied with a safety-valve to guard against undue pressure, which is, however, in all ordinary cases, kept down properly by the feed pump *n*, interposed between it and the boiler, and feeds it with pure highly heated water from the said case *e*, by which a large economy of heat is effected, and lightness of construction of case *e* and tubes *b* attained.

Having thus fully described my invention and its purposes, what I claim therein as new, and for which I desire Letters Patent, is—

1. The combination of apparatus for transferring the water of condensation to the boiler, highly heated, by passing it through the case containing the condenser, said apparatus consisting of the vacuum pump, case *e*, and pump *n* that forces the water from the case *e* into the boiler, substantially as and for the purposes set forth.

I also claim arranging the coils of pipe *h* within the case *e*, above the base-plate *f*, and in combination with the chambers *a* as specified.

I also claim the conjoint arrangement of pipes *h* and pipes *k*, substantially as herein described.

I also claim the combination of the chambers *a b*, case *e*, vacuum and feed pumps *l* and *n*, arranged and combined substantially as and for the purposes herein made known.

J. M. MILLER.
